DISPENSING-CABINET.

1,273,280.

Specification of Letters Patent. Patented July 23, 1918.

Application filed June 5, 1914. Serial No. 843,115.

To all whom it may concern:

Be it known that we, PAUL A. SCHUCHART, a subject of Austria, and GOUVERNEUR G. BROWN, a citizen of the United States, both 5 residing at New York city, county of Kings, and State of New York, have invented certain new and useful Improvements in Dispensing-Cabinets, fully described and represented in the following specification and the 10 accompanying drawings, forming a part of the same.

This invention relates to dispensing cabinets of that class used for delivering interleaved sheets, the especial object being to 15 provide an improved cabinet for use particularly with paper towels, napkins, and the like, although applicable also to other uses.

One of the especial objects of the invention is to provide a cabinet which will avoid 20 the difficulty in starting a sheet through the delivery slot, in case the usual projecting end of a sheet is missing, due to incorrect action of the sheet or from other causes, this difficulty being avoided in accordance 25 with the present invention by making the bottom of the cabinet slotted or otherwise providing it with openings independent of the delivery slot that are of sufficient size 30 to enable a sheet to be readily manipulated for starting its leading end through the delivery opening or for removing a damaged sheet, while at the same time substantially preventing the withdrawal of any considerable 35 number of sheets, which construction, also, aids materially in reducing the friction on the sheets and securing their proper delivery, and preferably is formed of fingers extending in the direction of the delivery 40 movement of the sheet.

A further object of the invention is to provide an improved construction for facilitating the rolling of the sheet in delivery, so as to lessen the resistance to the delivery 45 pull on the sheet resulting from the weight of the sheets above it. This result is secured by providing spaces in the bottom of the cabinet, extending longitudinally of the delivery slot and throughout the length of the 50 sheets, into which spaces the sheets may roll as they are drawn toward the delivery slot,

such spaces preferably being formed by curved depressions in the bottom of the cabinet or the fingers above referred to, when such fingers are used.

The invention includes in addition to the above features, various features of construction and combination of parts, all as fully described hereafter and pointed out in the 55 claims.

In the accompanying drawings forming a part of this specification, there is shown for purpose of illustration, a cabinet for interleaved towels, napkins, or the like, embodying all the features of the invention, in 60 which

Figure 1 is a front view of the cabinet in place on the wall, partly in section to show the sheets.

Fig. 2 is an end view of the cabinet.

Fig. 3 is a cross section through the cabinet with sheets therein.

Fig. 4 is a longitudinal section of the cabinet without the sheets.

Fig. 5 is a reverse plan view of the cabinet without the sheets.

Fig. 6 is an enlarged detail, corresponding to Fig. 3, showing the operation of withdrawing a sheet.

Referring to the drawings, A is the outer 80 casing of the cabinet, shown as a box having an open bottom and open ends, and adapted to be attached to the wall, as by backing plate B, to which the box is secured.

Within the box A is the inner casing or 85 holder C, adapted to be slipped up into box A, which holder preferably and as shown has an open top and open front and rear sides, but closed ends, so that box A and holder C fully inclose the sheets in the dispensing position, although the box and 90 holder are lightened and cheapened as far as possible.

The holder C is dropped in the box A for filling through the open side without removing the holder from the box, or 95 by removing and inserting it through the bottom of the box, if preferred. As shown, the holder C is held in its upper or dispensing position in the box by spring clips 1, catching over the top of the box, and the 100 holder is held in its lowered or filling position in the box by stops 2 engaging the

bottom bars or stops 3 on the box when the holder is lowered. It will be understood that any other suitable devices for connecting the holder and box or locking them in dispensing 5 position may be used.

The bottom of the holder C is preferably formed, as shown, by series of fingers 10 extending inward from opposite sides of the holder transversely to the delivery slot for 10 the sheet, which slot in the preferred construction shown, is placed at about the middle of the holder. These fingers 10 may be used without any connection or support adjacent to the delivery slot, but preferably 15 the fingers will be connected and supported at their inner ends, this being done in the construction shown, by rods 11, mounted in the ends of the holder and extending along the under side of the respective series of 20 fingers 10. These rods not only support and strengthen the fingers 10, so that they may be made of light material, but aid also in preventing the ready withdrawal of any considerable number of sheets. The same re- 25 sult of preventing the ready withdrawal of the sheets may be secured, of course, by any continuous connection between the ends of the fingers adjacent to the delivery slot, whether or not such connection serves also 30 to strengthen and support the fingers. The fingers 10, as shown, are formed with portions 4 at opposite ends of the fingers, that is, next the wall of the holder and next the delivery slot, which portions act to support 35 the pile of sheets α , and with intermediate portions 5 depressed below the normal level of the pile of sheets, and of such extent transversely to the delivery slot, as to provide for the rolling therein of the sheet being with- 40 drawn through the delivery slot and the delivery end of the next sheet folded therein. This reduces the friction upon the sheets in withdrawal, and aids materially in securing the ready and proper delivery of the sheets. 45 The action of these depressions in the withdrawal of a sheet is illustrated in Fig. 6.

It will be understood that the invention is not to be limited to the specific form or arrangement of parts illustrated, but that 50 many modifications may be made therein, while retaining the invention defined by the claims.

What is claimed is.

1. A dispensing cabinet for interleaved 55 sheets having a delivery side with a delivery slot and having its delivery side provided with openings independent of the delivery slot for convenient manipulation of a sheet.

60 2. A dispensing cabinet for interleaved sheets having a delivery side with a delivery slot, and having its delivery side slotted independently of the delivery slot.

65 3. A dispensing cabinet for interleaved sheets having a delivery side with a delivery

slot, and having its delivery side slotted transversely to the delivery slot for access to the sheets independently of the delivery slot.

4. A dispensing cabinet for interleaved sheets having a delivery side with a delivery slot, and slotted transversely to the delivery slot for access to the sheets independently of the delivery slot, said transverse slots being closed at their ends next the delivery slot. 70

5. A dispensing cabinet for interleaved sheets having a delivery side with a delivery slot and formed of fingers extending transversely to the slot, said fingers being separated to provide spaces for access to the sheets independently of the delivery slot. 75

6. A dispensing cabinet for interleaved sheets having a delivery side with a delivery slot and formed of fingers, said fingers being separated to provide spaces for access to the sheets independently of the delivery slot, 80 and a continuous connection between the ends of the fingers adjacent to the delivery slot. 85

7. A dispensing cabinet for interleaved sheets having a delivery side with a delivery slot and formed of fingers at opposite sides of the slot extending transversely to the slot, said fingers being separated to provide spaces for access to the sheets independently of the delivery slot, and supporting rods 90 extending between the walls of the cabinet longitudinally of the delivery slot and supporting the fingers near the delivery slot. 95

8. A dispensing cabinet for interleaved sheets, having a delivery side with a delivery slot and formed of separate fingers extending transversely to the slot, said fingers being formed with depressions to provide space for the rolling of the sheets in delivery. 100

9. A dispensing cabinet for interleaved sheets having a delivery side with a delivery slot and slotted transversely to the delivery slot for access to the sheets independently of the delivery slot, said delivery side being provided with depressions to provide space for the rolling of the sheets in delivery. 110

10. A dispensing cabinet for interleaved sheets having a delivery side with a delivery slot and formed of fingers at opposite sides of the slot extending transversely to the slot, said fingers being formed with depressions to provide space for the rolling of the sheets in delivery. 115

11. A dispensing cabinet for interleaved sheets having a delivery slot and a support for the edge of the pile of sheets and having a portion of its delivery side between the slot and support depressed below the level of said support to provide space for the rolling of the sheets in delivery. 120

12. A dispensing cabinet for interleaved sheets having a delivery slot and supports for the edges of the pile of sheets on opposite sides of the slot and having its delivery side 125 130

provided with curved depressions between the supports and slot extending below the level of said supports and throughout the length of the sheets to provide space for the 5 rolling of the sheets in delivery.

13. A dispensing cabinet for interleaved sheets having a delivery slot and supports for the edges of the pile of sheets on opposite sides of the slot, and having its delivery 10 side provided on both sides of the delivery slot between the supports and slot with depressions extending below the level of said supports and throughout the length of the sheets to provide spaces for the rolling of the 15 sheets in delivery.

14. A dispensing cabinet for interleaved sheets having its bottom formed of two sets of fingers 10 extending inward from the opposite sides of the sheet holder with space 20 between the adjacent ends of the fingers to form the delivery slot.

15. A dispensing cabinet for interleaved sheets having its bottom formed of two sets

of fingers 10 extending inward from the opposite sides of the sheet holder with space 25 between the adjacent ends of the fingers to form the delivery slot, said fingers 10 having depressed portions 5.

16. A dispensing cabinet for interleaved sheets having its bottom formed of two sets 30 of fingers 10 extending inward from the opposite sides of the sheet holder with space between the adjacent ends of the fingers to form the delivery slot, said fingers 10 having depressed portions 5, and rods 11 closing 35 the slots between the fingers at their inner ends and supporting the fingers.

In testimony whereof, we have hereunto set our hands, in the presence of two subscribing witnesses.
